SAFETY SWITCH TOGGLE

Ralph W. Shifley, O'Fallon, Mo., assignor to Emerson
Electric Co., St. Louis, Mo.

Filed Dec. 23, 1970, Ser. No. 26,628

Term of patent 14 years

Int. Cl. D13—03

U.S. Cl. D26—13

FIG. 1

FIG. 2

FIG. 3

FIG. 4

FIG. 5

FIG. 8

FIG. 6

FIG. 7

FIG. 1 is a perspective view of one embodiment of a safety switch toggle;

FIG. 2 is a perspective view of another embodiment of a safety switch toggle;

FIG. 3 is a view in side elevation of the safety switch toggle illustrated in FIG. 1;

FIG. 4 is a bottom plan view of the safety switch toggle illustrated in FIG. 1;

FIG. 5 is a view in perspective of a safety key part of the safety switch toggle of this invention, shown intermounted in FIG. 1 and FIGS. 3-4;

FIG. 6 is a view in side elevation of the safety switch toggle illustrated in FIG. 2;

FIG. 7 is a bottom plan view of the safety switch toggle illustrated in FIG. 2; and

FIG. 8 is a view in perspective of a safety key shown intermounted in FIG. 2 and FIGS. 7-8.

The broken line portions of the figures are for illustrative purposes only.

I claim:

The ornamental design for the safety switch toggle, as shown and described.
